ANCHORING MEANS

Warren Noble, Michigan City, Ind., assignor, by
mesne assignments, to Safety Mining Com-
pany, Chicago, Ill., a corporation of Illinois

Application February 28, 1934, Serial No. 713,338

9 Claims. (Cl. 102—11)

This invention relates to blasting or material-breaking cartridges of that type which comprises usually a rigid container within which a high pressure is adapted to be built up, and which is 5 adapted to release its charge of highly compressed gas when a predetermined pressure has been attained, or at the will of the operator; and the invention relates more particularly to safety devices for anchoring such shells or cartridges 10 in the material to be broken down, to prevent their being violently ejected from the face, and providing a seal for the hole.

As is well known, there are a number of varieties of shells or cartridges used in the breaking down of coal and which are adapted to be lodged in holes bored into the material to be broken down and, after the generation in, or introduction of pressure to, said cartridges, to release their charges and thereby break down 20 the material. Many such cartridges release the pressure contained within them either at or near the inner end of the hole in which they are lodged in the material to be broken; and the breaking medium under high pressure therefore 25 tends to act upon the air-cartridge or shell as does the burning powder in the barrel of a gun upon the bullet, the position of the shell being comparable to that of a bullet near the breech of a gun, and the released charge of pressure 30 medium tending to force the shell outwardly, and, after displacing the tamping, violently to eject the shell from the hole, with the possibility of serious injury to any one nearby.

A very satisfactory form of shell is loaded into 35 the hole empty, and a high pressure is then produced therein, as by storage therein of a substantial quantity of gas at high pressure by means of a pump located near the working face. It is one of the objects of the present invention to 40 provide a safe and highly effective anchoring means for such a shell. In the anchoring of a shell of this character, it is desirable not to rely upon a single anchoring element. It is desirable, moreover, to be able to provide, in the event of 45 taper in the hole drilled, for anchoring devices which will act upon walls of different diameter and still hold the shell in position. It is also desirable, and I have provided means whereby it is possible, to cause the charging of the cartridge 50 to render the anchoring means effective, whereby the cartridge may be placed in the hole without difficulty and then automatically anchored. It is further desirable that the anchoring prior 55 to the release of the blasting charge means be readily adjustable so as to permit the appli-

cation of the anchoring force at different positions in the material, at the option of the miner who is doing the shooting.

Another object is to provide an improved automatic seal for the drill hole for preventing 5 leakage of blasting pressure past the cartridge through the hole.

It is another object of my invention to provide an improved anchoring means which shall accomplish the several beneficial results just enumerated, so that a maximum of adaptability, 10 convenience and effectiveness may be attained. Other objects and advantages of the invention will hereinafter more fully appear.

In the accompanying drawing, in which one 15 form of the invention is shown for purposes of illustration,—

Fig. 1 is a side elevational view of a blasting cartridge provided with an anchoring means constructed in accordance with the illustrative em- 20 bodiment of the invention.

Fig. 2 is a longitudinal section through the anchoring means proper, the fluid supply means at one end of the cartridge, the section being 25 on two angularly related, radial planes.

Figs. 3, 4, 5, 6, 7, 8, and 9 are transverse sections through different parts of the anchoring means all of these sections being taken on planes corresponding to the several lines 3—3, 4—4, 5—5, etc. of Fig. 2. 30

Fig. 10 is a detail on a somewhat enlarged scale, showing the inlet valve construction.

Referring to the drawing, it will be noted that the shell member 1, which may be of any suitable construction and provided with any desired 35 and suitable releasing means—for example, a charge releasing means of the character shown in my copending application Serial No. 713,337, which I am executing of even date herewith, is mounted in a drilled hole 2 in the material to 40 be broken down, 3. The shell 1 comprises a casting member 4 having a large, internal charge receiving chamber 5 and adapted, in the present case, upon the attainment of a predetermined desired maximum internal pressure, to release its 45 charge through an annular passage 6. One mechanism whereby this release can be effected as specified, is disclosed in my copending applica- 50 tion mentioned.

At its rear or outer end, the shell 1 is provided 50 with a reduced externally threaded portion 7 to which there is threadedly connected a clamping collar 8 having holes 9 for the reception of a lever (not shown) by means of which a tight 55 clamping action may be effected. By means of

the member 8 there is clamped to the shell a combined self-tamping and air supply mechanism, all of which is generally designated 10. The self-tamping device comprises a tamping or hole gripping means proper and actuating means for the latter. Herein, it will be observed that a hollow member 12 having an external shoulder 13 is adapted to be clamped, by means of its shoulder 13, in position to the end of the shell 1. The member 12 comprises a bore of two diameters, the larger bore, 14, lying herein wholly within the outer end of the shell casing, and the smaller bore, 15, extending outwardly from the bore 14 to the rear end of the member 12. The member 12 is provided with an external buttress thread 16, herein extending substantially throughout the entire length of the portion thereof which extends outwardly from the clamping collar 8. Within the bore 15 is mounted, for longitudinal sliding movement, a member 18 providing a fluid supply passage 19 opening at 20 into the chamber 5 within the shell, there being a suitable packing provided at 21 to prevent leakage of fluid from within the shell into the space within the bore 14. The member 18 is provided with an enlarged collar or piston portion 22 slidable within the bore 14; and rubber or other suitable packing rings 23 and 24 are arranged to preclude leakage inwardly past the collar 22 and outwardly along the member 18; and a small port 25 communicating with the passage 19 and having a small end-seating control valve 26 having a longitudinal pressure transmitting groove 27, is arranged to admit pressure from the passage 19 into the space between the packings 23 and 24. A small elastic ring 28 surrounds the member 18 and passes over the outer end of the valve 26 and normally maintains the same seated.

Upon the buttress-threaded exterior of the member 12 there are arranged any desired number of self-tamping devices which are adapted to be rendered effective by movement of the member 18 upon admission of fluid through the passage 25 to act upon the packing 24 and collar 22 to effect longitudinal movement of the member 18. Each of the self-tamping devices includes a ring-expanding member 30 (the several members distinguished by different alphabetical exponents) having a conical surface 31 which tapers in the direction of shell re-action. Cooperating with each of the conical surfaces 31 is a friction anchoring and hole sealing ring 32 of rubber or other suitable material having a high coefficient of friction and capable of expansion when thrust longitudinally of its cooperating conical surface 31 toward the base of such conical surface. It will be understood that the members 30 threadedly engage the buttress thread 16 and are adapted to be positioned at any desired point along the latter. Each of the members 30 is traversed by a plurality of holes parallel to its axis, for a purpose which will shortly be described. Each of the self-tamping devices also includes a pressure ring 35 having a central opening 36 therethrough, of suitable size to permit sliding upon the outside of the threaded member 12, and these rings also have holes through them as later described. Exponents are used for clarity with respect to a number of the parts and holes.

The means for forcing the rings 32 up their cooperating cones and into frictional engagement with the bore of the hole, will now be described.

For the purpose of distinguishing, in the follow-

ing description, between the component elements of the different sets of self-tamping devices, the component parts of the device nearest the shell body will be called 30^a, 32^a, and 35^a; those in the next self-tamping device will be designated 30^b, 32^b, and 35^b, and those of the device nearest the mouth of the hole will be designated 30^c, 32^c, and 35^c. It will be understood that, depending upon the depth of the hole and the length of the threaded portions of the member 12, any desired number of self-tamping devices may be employed; and appropriate means is provided so that these several devices may be each caused to effect its gripping function through direct application of force thereto independently of elements of the other. For the purpose of accomplishing this highly important function, a common actuating element is provided, in the form of a member 40 threadedly engaged at 41 with the outer end of the member 18. The air supply line 42, leading from a suitable pump or compressor, may here be noted to enter a chamber 43 formed in the end of the member 18, and to be provided with a suitable self-sealing and locking glandular connection 44 therewith. The member 40 is adapted, upon longitudinal movement toward the shell by reason of the action of air upon the piston 22, to impart pressure independently to each of the three ring members 35^a, 35^b, and 35^c through rod elements individual to the several ring members mentioned. A fourth cone member, in the construction shown, is provided at 30^d for the purpose of retaining the ring 35^d in position. The member 30^d, shown in section in Fig. 3, will be observed, as herein illustrated, to be traversed by nine holes, constituting three sets of three each, the holes in each set being arranged 120° from each other and the three sets being equally spaced. The holes in this member are numbered 45^a, 46^a, 47^a, 45^b, 46^b, 47^b, and 45^c, 46^c, 47^c. The member 35^c, shown in Fig. 7 and the member 30^c, shown in Fig. 4, are traversed by six holes each, so arranged that they may be disposed in alignment with six of the nine holes in member 30^d. The holes in the member 35^c are numbered, severally, 48^a, 49^a, 50^a, and 48^b, 49^b, 50^b, while those in the member 30^c are numbered 51^a, 52^a, 53^a, and 51^b, 52^b, 53^b. The member 35^b, shown in Fig. 8, is traversed by three holes in alignment with three of the holes in members 30^c and 35^c, and designated 54^a, 55^a, 56^a. The member 30^b, shown in Fig. 5 is traversed by six holes, three in alignment with the holes in the member 35^b and three in addition. The first three holes are designated 57^a, 58^a, 59^a, and the second series, 57^b, 58^b, 59^b. The member 35^a (Fig. 9) is traversed by three holes, in alignment with the last three holes mentioned, in element 30^b, and designated 60^a, 61^a, 62^a; and member 30^a (see Fig. 6) is traversed by three holes, in alignment with the holes in member 35^a, and designated 63^a, 64^a, 65^a. With the several series of holes mentioned, different sets of pusher rods and guides cooperate. Thus, three relatively short pusher rods, all of equal length and numbered, severally, at 66^a, 67^a, 68^a, extend respectively through the guide holes 45^a, 46^a, 47^a in the member 30^d, and engage, with their ends toward the shell, the end surface of the member 35^c; and are adapted, when their other ends are pressed by the member 40, to thrust the member 35^c longitudinally and thereby press the member 32^c along the conical surface of the member 30^c, and expand the member 32^c into 75

tight engagement with the wall of the hole. Longer rods 70^b, 71^b, 72^b extend from a point adjacent the pressure member 40 through the holes 45^b, 46^b, 47^b in the member 30^a, through the holes 48^b, 49^b, 50^b, in the member 35^c, and through the holes 51^b, 52^b, 53^b in the member 30^c, and engage the end surface of the member 35^b, and are adapted to act upon the latter to force the ring 32^b along the conical surface 31^b and cause frictional gripping of the wall of the hole. A series of still longer rods, 74^a, 75^a, 76^a, extend from a point adjacent the pressure applying member 40, through all of the holes bearing designations terminating in "a" in the members 30^a, 35^a, 30^c, 35^b, and 30^b, and are adapted to engage the end of the member 35^a to force the ring 32^a along the cone 30^a and to expand the ring thereby into frictional engagement with the wall of the hole.

Positioning rods 78^c, 79^c, 80^c traverse the holes having the letter "e" as an exponent in their reference characters, in the members 30^b, 35^c and 30^a.

It will be noted that any change in adjustment of any of the cones relative to each other is prevented by the rods passing through the several series of holes mentioned. It will further be noted that the pressure which is applied to each of the pressure plates or rings is transmitted directly thereto, and not through one of the other rings. It will further be noted that by adjusting the rod lengths in the different series, it is possible to effect any desired positioning of the self-tamping anchor devices, and that by varying the initial positions of the cone members 30^a, 30^b or 30^c relative to the pressure applying members, different overall dimensions of the rings when in fully expanded position may be obtained.

From the foregoing description, the mode of operation of the improved self-tamping anchoring devices will be clearly apparent. Upon the supply of fluid through the line 42 to the interior of the shell, pressure will be gradually built up within the interior of the shell, and when a sufficient pressure, herein substantially below the blasting pressure, has built up to unseat the conical portion of the valve 26 from its seat, a small quantity of pressure fluid will flow through the groove 27 into the space between the rings 23 and 24 and, acting through the piston collar 22, will move the member 18 longitudinally and cause the member 40 to apply pressure to the several series of rods described. The rods will, in their turn, apply pressure to the followers or pressure plates 35^a, 35^b, 35^c, and these will force their several rings 32^a, 32^b and 32^c upwardly along the conical surfaces 31^a, 31^b and 31^c, and effect a very positive locking or anchoring of the cartridge in place. Any tendency of the shell to be blown out of the hole will cause the rings 32^a, 32^b, and 32^c to tend to roll further up their respective conical elements, and will increase the locking force. Obviously, rings can be multiplied by increasing the number of holes. For example, by inserting three more series of holes in the spaces between the several series illustrated, twice as many self-tamping devices could be provided. It will be noted that the present arrangement is attachable to or detachable from the shell as a whole; that the anchoring capacity is literally tremendous, and that it may be increased or diminished, as may be necessary, depending upon the nature of the material, merely by adding or removing tamping units with the actuating rods

therefor. In the event that there is any tendency for leakage past the packing 24 and the piston 22, a very minute vent could be arranged to carry away fluid from the space to the left of the collar 22; and if desired, suitable provision can be made for permitting release of pressure from the space beyond the valve 26 when it is desired to collapse the anchoring device. As pointed out above, adjustment of the cone elements 30 permits the adapting of the anchoring or tamping devices to tapered or rippled holes; and, as also pointed out above, if the material in which the hole is drilled is relatively soft, the number of anchors can be increased at will.

While I have in this application specifically described one form which my invention may assume in practice, it will be understood that the invention may be modified and embodied in various other forms without departing from its spirit or the scope of the appended claims.

What I claim as new and desire to secure by Letters Patent is:—

1. An anchoring device comprising a cone, an expandible anchor ring, and means including a fluid actuated piston for forcing said ring towards the base of said cone while the latter remains relatively stationary to expand the ring into an anchoring position.

2. An anchoring device comprising a cone, an expandible anchor ring, and means for forcing said ring towards the base of said cone while the latter remains relatively stationary including a pressure plate and pneumatic thrusting means therefor.

3. An anchoring device insertible in a bore hole comprising expandible anchoring and hole sealing means adapted to grip completely about the bore hole walls, and means embodied in said device and operated by pressure fluid for expanding said anchoring means and for holding the latter expanded.

4. An anchoring device insertible in a bore hole comprising expandible anchoring means adapted to grip completely about the bore hole walls, and wedge means embodied in said device and operated by pressure fluid for expanding said anchoring means and for holding the latter expanded.

5. A blasting cartridge adapted for insertion in a blast hole and having associated therewith an anchoring and hole sealing device having means for gripping completely about the bore hole walls to seal the hole, and means operable automatically on charging of said cartridge and by a portion of the charging pressure being fed to the carriage to effect anchoring of the cartridge in the blast hole and sealing of the hole.

6. A blasting cartridge having associated therewith a hole sealing device, and means operable automatically on charging of said cartridge and prior to the delivery of any blasting force to the material being blasted for effecting sealing operation of said hole sealing device.

7. A blasting cartridge having associated therewith a hole sealing device for sealing the bore hole at the outer end of the cartridge comprising a sealing unit, and pressure fluid operated means for effecting sealing operation thereof comprising means supplied with pressure fluid from the supply line to said cartridge.

8. An anchoring device comprising a tubular member, an anchoring element mounted thereon, a member movable relative to said tubular member for moving said anchoring element into an anchoring position, and an element movable axially

within said tubular member for moving said moving member.

9. An anchoring device comprising a tubular member, an anchoring element mounted thereon, a member movable relative to said tubular member for moving said anchoring element into an-

anchoring position, and an element movable axially within said tubular member for moving said moving member including a pressure fluid actuated piston secured to said axially movable element.

WARREN NOBLE.
